Primary Examiner — Robert M. Spear*Assistant Examiner* — Darcey E Heflin(74) *Attorney, Agent, or Firm* — Norton Rose Fulbright Canada LLP(57) **CLAIM**

I claim the ornamental design for a food container lid, as shown and described.

DESCRIPTION

FIG. 1 is a perspective view of a food container lid in accordance with the present design;

FIG. 2 is a front face view of the food container lid of FIG. 1, a rear face view being a mirror image thereof;

FIG. 3 is a right-side face view of the food container lid of FIG. 1, a left-side face view being a mirror image thereof;

FIG. 4 is a top view of the food container lid of FIG. 1; and,

FIG. 5 is a bottom view of the food container lid of FIG. 1. The broken line portions are included to show environmental subject matter only and form no part of the claimed design.

1 Claim, 4 Drawing Sheets(56)
